UNITED STATES PATENT OFFICE.

GEORGE A. ANDERSON, OF DIXON, ILLINOIS.

TAMPING DEVICE.

1,218,615.

Specification of Letters Patent. Patented Mar. 13, 1917.

Application filed January 24, 1916. Serial No. 73,828.

To all whom it may concern:

Be it known that I, GEORGE A. ANDERSON, a citizen of the United States, residing at Dixon, in the county of Lee and State of Illinois, have invented certain new and useful Improvements in Tamping Devices, of which the following is a specification.

My invention relates to tamping devices, of that class which are used in connection with concrete formations, in the manufacture of bricks, in foundry work, and for similar operations. Some of the purposes of the present invention are to provide a simpler means for the operation thereof, and also greatly increase the range of usefulness of the machine.

In the drawings: Figure 1 shows my invention in perspective, in position when in use. Fig. 2 is a detail of the frame supporting devices, transversely of the frame.

1 represents a circular track adapted to be attached to the ceiling of a room by means of brackets 2 connected therewith. Supported on the track 1 is a carrier 3, by means of rollers 4 on the carrier which engage the upper edge of the track. Depending from the carrier 3 is a support 5 provided on its lower end with a head 6, upon which is pivoted a head 7, so as to have rotatable movement in a horizontal plane. Fixed to the hub 7 so as to project radially therefrom in opposite directions is a pair of shafts 8, upon which are rockingly supported the side arms of a frame 9 by means of bearings 10 pivoted near the outer ends of said shafts.

Near one end of the frame 9 is rotatably mounted a shaft 11 on which is supported a casing 12, from which depends a tube 12', within which is a rod 13, connected with the shaft 11 by any suitable devices whereby such rod may be suitably reciprocated. Such devices may be similar to those shown in Letters Patent of the United States No. 941,033 issued to me November 23rd, 1909, for improvements in mechanical movements. On the lower end of the rod 13 is a tamping tool 14.

Fixed to the shaft 11 is a pulley 15 connected by a belt 16 with a pulley 17 rotatably mounted on one of the shafts 8. Adjacent to the pulley 17 and rotatable therewith is a pulley 18 driven by a belt 19 from a pulley 20 on a shaft 21 of an electric motor 22 mounted on the frame 9 at

that end thereof opposite to the tamping devices. When the motor is in operation movement is imparted through the pulleys 17 and 18 and belt 16 to the wheel 15, rotating the shaft 11 and actuating the tamping devices. The motor can be operated from any source of electrical power by means of wires 23 running thereto.

Rotatably mounted on the support 5 is a collar 24, to which is attached one end of a rod 25, the opposite end thereof being connected with the frame 9 at the tool end thereof. Between its ends said rod is provided with a contractile coiled spring 26, the function of which is to return the frame 70 to a horizontal position after the tool end thereof has been tilted downwardly. The opposite end of the frame 9 is similarly returned to a horizontal position by means of a rod 27 connected with that end of the frame at one end and with the collar 24 at the other, and provided with a coiled spring 28, permitting a yielding extension of said rod.

In operation the frame 9 can be rocked 80 downwardly or upwardly to any desired position, and can be rotated in a circle on the support 5. Said support being movable on the track 1 renders it possible to shift the device to a great variety of positions. 85 The track can be made of any desired size, and can be made straight instead of in a circle, or of any desired shape.

The motor 22 is not only in a convenient position to follow the movements of the tool 90 13, and maintain its position with relation thereto, but it also serves as a counterbalance to overcome the weight of the tamping devices at the opposite end of the frame.

It has been usual to operate a machine of this kind with overhead shafting and gearing, and the arrangement herein shown and described greatly lessens the number of operative parts, and correspondingly simplifies the machine. It also has a great amount 100 of freedom of action which the former machines did not have, being limited as they were to one spot.

What I claim as my invention and desire to secure by Letters Patent of the 105 United States, is:

1. A device of the class described, comprising a circular track adapted to be secured to an overhead support; a carrier movable on said track; a hub pivotally sup- 110

ported from said carrier; a frame rockingly mounted on said hub; a tool carried by one end of said frame; a motor mounted on the opposite end of said frame; and means for 5 imparting the movement of said motor to said tool to suitably operate the same.

2. A device of the class described comprising a support; a frame connected with said support so as to be capable of universal 10 movements; a tool supported at one end of said frame; a motor mounted on the opposite end of said frame and acting as a counterbalance for said tool; and means for imparting the movement of said motor to said 15 tool, to suitably operate the same.

3. In a device of the class described, the combination of a support; a frame connected therewith so as to be capable of universal movements; a tool carried by one end of 20 said frame; a counterbalance on the opposite end of said frame; and means for yieldingly controlling the movement of said

frame in its movement out of a horizontal plane.

4. A device of the class described, comprising an overhead support; a supporting member depending therefrom; a hub pivotally mounted on said supporting member; a frame rockingly mounted on said hub; a tool carried by one end of said 25 frame; a motor mounted on the opposite end of said frame and acting as a counterbalance for said tool; means for imparting the movement of said motor to said tool, to 30 suitably actuate the same; and means for yieldingly controlling the action of said frame in its rocking movement.

In testimony whereof I affix my signature in presence of two witnesses.

GEORGE A. ANDERSON.
